STORE FRONT CONSTRUCTION

Harry Ernstoff, Brooklyn, N. Y.

Application November 23, 1933, Serial No. 699,413

8 Claims. (Cl. 20—56.4)

The present invention relates to window frames and has for its main object the provision of window frames so constructed as to facilitate the mounting of the glass window and the removal and replacement thereof. The construction of this invention is intended primarily for use in connection with store fronts in which plate glass windows are employed but may be used and will be found advantageous in other relations.

An object of this invention is the construction of the frame whereby the molding which normally overlies the marginal edge portion of the glass plate can be built into the frame as a permanent part thereof and the glass plate can be mounted in and removed from the frame without removing the molding.

Another object is to provide a window frame molding of improved construction.

A further object of the invention is to provide a molding construction in which it is unnecessary to use screws or other securing devices passing through or in contact with the glass plate for securing the molding in position.

A further object of the present invention is generally to provide an improved store-front construction.

For a complete understanding of the invention reference is to be had to the following description considered in connection with the accompanying drawings forming a part of this specification.

In the drawings:

Fig. 1 is a front elevation of a store front embodying the present invention;

Fig. 2 is a section on the line 2—2 of Fig. 1;

Fig. 3 is a vertical sectional view;

Fig. 4 is a vertical section of the upper part of the frame;

Fig. 5 is a rear view in elevation of the upper part of the frame; and

Fig. 6 is a section on the line 6—6 of Fig. 5.

Referring to the drawings in detail, there is shown a store front comprising a base 10 and a window frame 11 having an opening in which there is mounted a glass window 12 which, as in the usual store front constructions, is made of plate glass.

The upright members 13 and 14 of the frame have vertically extending grooves 15 and 16 and the sill 17 has a groove 18. Within these grooves are mounted side and bottom frame members or moldings of the improved construction of the present invention for removably holding the glass plate 12.

As shown more clearly in Fig. 2, each of the side moldings comprises a front portion 19 and a spaced rear portion 20 united by a projecting side portion 21 outlining a vertically extending groove 22 for receiving the glass plate 12. As shown in Fig. 3 the bottom molding is of the same construction as the side moldings and comprises a front portion 23, a rear portion 24, and an intermediate projecting portion 25 outlining a groove 26 within which the lower marginal edge portion of the glass plate 12 is received. The intermediate projecting portions 21 and 25 of the side and bottom moldings are secured within the grooves 15, 16, and 18 in the side uprights and in the sill of the frame 11 so that the side and bottom moldings may if desired be built into the frame and form a permanent part thereof, although it will be understood that these moldings may be removably secured to the frame. The grooves 22 and 26 are somewhat wider than the thickness of the glass plate 12 and the groove 22 in one of side moldings, here shown in the left side molding, is deeper than the groove 22 in the right side molding, so that the glass plate 12 may be moved to the left (as viewed from Fig. 2) an amount sufficient to permit the opposite vertical edge of the glass plate 12 to clear the front portion 19 of the corresponding side molding. However, both grooves 22 may be of equal depth provided they are deep enough to permit the glass plate to be moved far enough into one groove so that a side edge of the plate will clear the adjacent side molding. The moldings are provided with ventilating means constituted by apertures 22a and 23a in the side and bottom moldings respectively, extending from the front surface of the front portions of the molding to the grooves 22 and 26, respectively, and by grooves 20a and 24a in the side and bottom moldings, respectively, forming a means of communication between the grooves 22, 26 and the rear of the frame opening. Thus air may pass through the openings 22a and 23a for ventilation and other well known purposes and water which may accumulate in the window frame from condensation or when the window is washed may escape through the openings 23a in the bottom molding. The ends of the moldings are beveled forming miter joints indicated in dotted lines in Fig. 1 and designated by the reference numeral 22b, the miter joints 22b at the top being shown in full lines in Fig. 5. Corner plates 22c overlie the bottom miter joints 22b and are secured to the side and bottom moldings in any suitable manner preferably by being soldered thereto. The top miter joints 22b are covered by plates 22d which are preferably

straight as shown and permanently secured only to the side moldings 19. These moldings may be made in one piece or of two pieces suitably fastened together and may be made wholly or partly 5 of wood or metal as may be desired. As here shown the moldings are made of wood and the front portions 19 and 23 are covered with metal.

At the upper part of the frame there is a top frame member or molding 27 which is mounted 10 for movement from the position shown in Fig. 3 where it overlies the top marginal edge portion of the glass plate 12 to the position shown in Fig. 4 above the top edge of said plate. For this purpose there are provided supporting and interengaging guiding means carried by the upper part 15 of the frame and molding 27 and comprising metal brackets 28 secured to the top of the frame 11 and slotted metal plates 29 secured to the molding 27. The construction is such that the slotted 20 plate 29 can move laterally of the bracket arm 30 between the positions shown in Fig. 3 and 4 so that any portions of the molding 27 such as the rib 31 projecting forwardly of the rear side 32 of the upper part of the frame will clear said 25 rear wall. When the molding 27 is in the position shown in Fig. 4 the glass plate 12 can be raised to permit the lower edge thereof to clear the upper edge of the bottom molding. It will be understood that there will be provided a sufficient 30 number of brackets 28 and slotted plates 29 to properly support the top molding 27, the number of these plates varying with the length of the molding.

In mounting the glass plate 12 in the frame the 35 top molding 27 is raised to the position shown in Fig. 4, the glass plate 12 is inserted preferably through the front of the frame with one vertical edge of said plate extending into a vertical groove 22 far enough to permit the opposite edge to clear 40 the adjacent side molding and to be moved rearwardly into alignment with the adjacent groove 22. The plate can then be lowered into the groove 26 in the bottom molding and centered with respect to the front portions 19 of the side moldings 45 so that said moldings overlie the marginal edge portions of the plate substantially as shown in Fig. 2. Then the top molding 27 is moved to the position shown in Fig. 3 where the lower portion thereof overlies the front of the top marginal edge 50 portion of the glass plate. A rear transverse frame member 33 is removably secured to the upper part of the frame 11, preferably to the side uprights 13 and 14, in overlying relation to the rear of the top marginal edge portion of the glass 55 plate and thereby holds the glass plate in position against the top molding 27 and the latter against the rear side 32 of the top front wall of the frame 11. Putty may then be applied as desired preferably in the space between the rear of the glass 60 plate and the walls of the grooves 22 and 26. In removing the glass 12, the transverse member 33 is removed and the top molding 27 is raised to the position shown in Fig. 4. Then the glass plate is moved to extend further into one of the 65 grooves so that one side edge will clear the adjacent side molding to permit the plate to be moved through the frame opening, preferably forwardly thereof, after the plate is raised so that its lower edge is clear of the bottom molding.

70 Thus, in the construction of this invention glass windows can be mounted, removed and replaced with comparatively no difficulty and it is unnecessary to remove or disturb the molding sections except only to displace the top molding 27. Accordingly the present construction has several

important advantages because the moldings are not subject to damage or destruction which frequently take place when it is necessary to remove them as in the prior art practice and the glass plate is not subject to the danger of cracking or breaking when, as in the prior art practice, screws or other securing devices usually passing through the glass plate are employed in fastening the moldings in position.

As here shown the base 10 of the present store front construction is ornamented by novel means comprising light reflecting means carried by the front plate 11 on the base 10. The light reflecting means is constituted by colored glass, known as cathedral glass, which, according to the present invention, is silvered or otherwise treated on its rear surface to form a reflecting surface. As here shown, the reflecting colored glass is in the form of a plurality of cubes or tiles 34, preferably of a plurality of contrasting colors, arranged to form a suitable design. The plate 11 may be of any suitable material such as marble or glass and is preferably of a color in contrast to the colors of the tiles 34 to form a background therefor. The tiles 34 are preferably set into a recess 100 in the plate 11 or into a recess outlines by a plurality of such plates, and the front surfaces of the tiles may be flush with the front surface of the plate 11, or may terminate below or project beyond said surface as desired.

While, as required by the patent statute, I have shown the preferred embodiment of my invention, it will be understood that the latter is capable of other specific embodiments and certain changes in the construction and arrangement of 110 parts may be made without departing from the invention as defined by the appended claims.

Having thus described my invention, I claim:

1. A window frame comprising grooved side and bottom walls for receiving the marginal edge 115 portions of a glass plate, and a top wall for overlying the top marginal portion of said glass plate, said top wall mounted on the frame for movement upwardly and laterally of the top edge of the glass plate.

2. A window frame for a glass plate, said frame having side and bottom portions adapted to normally overlie the front of the marginal side and bottom portions of said glass plate, said frame also having a top portion for normally overlying 125 the front of the marginal top portion of said glass plate, said top frame portion mounted for movement upwardly and rearwardly over the top edge of the glass plate.

3. A window frame comprising grooved side and bottom walls for receiving the marginal edge portions of a glass plate, and a top wall for overlying the front top marginal portion of said glass plate, said top wall mounted on the frame for movement upwardly and rearwardly over the top edge 135 of the glass plate.

4. A window frame having an opening for a glass plate, said frame having side and bottom portions adapted to normally overlie the front of the marginal side and bottom portions of said glass plate, and a top frame portion normally overlying the front of the marginal top portion of said glass plate and mounted for sufficient movement thereof upwardly beyond the top edge 140 of said glass plate to permit the lower edge of the glass plate to be raised above said bottom frame portion, said frame opening being wide enough to permit the glass plate to be moved laterally so that one side edge thereof can be 145

150 accordingly the present construction has several

moved beyond the normally overlying side frame portion.

5. A window frame having an opening for a glass plate, said frame having side and bottom portions adapted to normally overlie the front of the marginal side and bottom portions of said glass plate, and a top frame portion normally overlying the front of the marginal top portion of said glass plate and mounted for sufficient 10 movement thereof upwardly and rearwardly over the top edge of said glass plate to permit the lower edge of the glass plate to be raised above said bottom frame portion, said frame opening being wide enough to permit the glass plate to be 15 moved laterally so that one side edge thereof can be moved beyond the normally overlying side frame portion.

6. A window frame for a glass plate, said frame having side and bottom portions adapted to normally overlie the front of the marginal side and bottom portions of said glass plate, said frame also having a top portion for normally overlying the front of the marginal top portion of said glass plate, and means for mounting said top frame portion for movement upwardly and rearwardly of 20

the top edge of the glass plate, said means comprising relatively movable interengaging guiding means on said frame and said top frame portion.

7. A window frame for a glass plate said frame having side and bottom portions adapted to normally overlie the marginal side and bottom portions of said glass plate, said frame also having a top portion for normally overlying the marginal top portion of said glass plate, said top frame portion mounted for movement upwardly and laterally of the top edge of the glass plate. 80

8. A window frame having an opening for a glass plate, said frame having side and bottom portions adapted to normally overlie the marginal side and bottom portions of said glass plate, and a top frame portion normally overlying the marginal top portion of said glass plate and mounted for sufficient movement thereof upwardly beyond the top edge of said glass plate, said frame opening being wide enough to permit the glass plate to be moved laterally so that one side edge thereof can be moved beyond the normally overlying side frame portion. 85
